BURGLAR ALARM FOR CASH DRAWERS

Filed March 8, 1945

UNITED STATES PATENT OFFICE

2,416,963

BURGLAR ALARM FOR CASH DRAWERS

Francis C. W. Stelter, New York, N. Y.

Application March 8, 1945, Serial No. 581,661

10 Claims. (Cl. 177—314)

1

This invention relates to burglar alarms for cash drawers or tills, and more particularly to electric alarm systems adapted to actuate signal devices when the till is tampered with by unauthorized persons.

The general object of the invention is to provide a novel and improved device of the class described, which is economical to manufacture and install, simple in construction and operation, and thus well adapted to the needs of the average business man.

A more particular object is the provision of an alarm system which is adapted to be energized upon movement of the weighted guard or retainer which is usually provided to bear upon the paper money or currency in the appropriate compartments of the till.

In its preferred embodiment, the invention contemplates the provision of an alarm circuit including a source of current, a signal device such as a bell, and a switch device actuated by the pivotal movement of the guard frame which bears against the pile of bills or currency. The circuit may include switches actuatable by the guards in all of the compartments or by only one of them. In the latter case, preferably, the guard for the bills of higher denominations should be utilized.

A further feature of the invention involves the provision of a concealed manual switching device for breaking the circuit when it is not desired that the alarm shall be sounded.

A still further object of the invention is the provision of a concealed resetting device for the automatic alarm switch, the switch being of the type which will maintain the circuit closed until restored to its initial position. Thus, if the alarm is set off by accident the circuit may be immediately broken, and thus restored for normal functioning.

Other objects and features of novelty will be apparent from the following specification when read in connection with the accompanying drawings in which certain embodiments of the invention are illustrated by way of example.

In the drawings,

Fig. 1 is a top plan view of a cash drawer embodying the principles of the invention;

Fig. 2 is a fragmentary vertical sectional view through one of the compartments of the drawer, and taken on line 2—2 of Fig. 1;

Fig. 3 is a fragmentary transverse vertical sectional view taken on line 3—3 of Fig. 1;

Fig. 4 is a somewhat diagrammatic view in horizontal section, on a reduced scale, of a modified form of the invention; and

2

Fig. 5 is a fragmentary perspective view of the rear portion of a cash drawer illustrating a further modification of the invention.

The cash drawer or till illustrated in the first three figures of drawing is designated generally by the reference numeral 10, and comprises the two spaced side walls 11 which are mortised to receive the edges of the bottom wall 12, the front wall 13, and the rear wall 14 of the drawer. A series of partitions 15 extending fore and aft of the drawer 10 are provided, and these partitions together with the cross partitions 16 divided the drawer into a series of compartments. In this particular example, there are six compartments designated A and adapted to hold coins, and three compartments denoted by the letter B adapted to receive bills or currency.

An overhanging ledge 18 is provided adjacent the rear wall 14 of the drawer, and this ledge extends above the rear portions of the three currency compartments B.

The cash drawer 10 may be mounted or supported in any convenient way either beneath a counter or within a cash register. The drawer illustrated is of the latter type and is designed to ride upon anti-friction rollers carried by the frame of the cash register and illustrated somewhat diagrammatically at 19 in Fig. 3. Angular rails 20 are secured along the outer surface of the side walls 11 of the drawer, whereby the drawer is supported upon the rollers.

In each of the currency compartments B there are provided the weighted guard frames or clamps 25, these frames being preferably made of heavy wire bent into a generally U-shaped configuration, the forwardly extending bight of the frame carrying the weighted enlargement 26 which may be in the form of a roller which bears on the pile of bills in the compartment such as indicated at P in Fig. 2. The rear portions of the arms of the frame 25 are bent outwardly as at 27 and are pivotally received within the sockets 28 formed in the side wall 11 and in the partitions 15. Thus far, the arrangement is of conventional construction.

The novel alarm switch which forms an important feature of the present invention is designated generally by the reference numeral 29 and comprises the various elements described below. The rear wall 14 of the drawer is provided at least one point opposite the currency compartments B with an opening 30 in which a plunger 31 is adapted to move. The plunger may be made of metal or of insulating material since it forms no conducting part of the circuit, neither

is it likely to ground or short circuit any of the conducting parts of the switching arrangement. The head 32 of the plunger 31, in this particular embodiment, is provided by the screw 33 threaded into the end of the plunger. The screw clamps a metal washer 35 to the end of the plunger and this provides a laterally extending shoulder which constitutes one of the contacts of the switch. Beneath the flange or shoulder 35 and secured to the rear wall 14 of the drawer are the resilient metal leaves or contact blades 36. These blades may be attached to the wall as by means of the fastening elements 37 shown in Fig. 3, and the flared portions are bent to stand away from the wall 14 and to be resiliently contacted by the bridging contact portion 35 of the plunger.

The actuating connection between the guard 25 and the switch arrangement is provided by the rigid cross bar 38 which extends between the arms of the guard and is secured thereto as by means of the end sleeves 39. Centrally of the cross bar 38 an actuating finger 40 is provided which is adapted to bear against the head 32 of the plunger 31.

The rear end of the plunger 31 extends outwardly of the rear wall 14 and has a portion of its surface corrugated or serrated as at 42 so as to cooperate with the spring detent arm 43 secured to the rear wall 14. This provides holding means for releasably retaining the plunger in any position to which it is moved. Thus, when the guard 25 is raised by the removal of a bill from the pile P, the finger 40 will move the plunger 31 rearwardly until the bridging contact 35 presses against the resilient contact members 36, thus completing the alarm circuit. Regardless of the return of the guard frame 25 to the top of the pile P, the switch will be held in closed position by the detent elements 42, 43. In order to restore the switch, there is provided an angular lever arm 45 extending through an opening 46 in the rear wall and pivoted therein as at 47. The downwardly curved end 48 of the resetting lever 45 is arranged to contact with the rear end of the plunger 31 and the forwardly extending end 49 of the lever is concealed beneath the ledge 18 and may be manually lifted to restore the plunger 31 to its initial inoperative open circuit position, ready to be moved rearwardly by a subsequent displacement of the guard 25.

The electrical circuit is shown diagrammatically in Fig. 3 of the drawings. A battery 50 or other source of current is provided and is connected by means of the conductor 51 with one of the automatic switch blades 36. The other blade 36 is connected by means of the wire 52 to a terminal 53 of the manually actuatable switch 54 which is secured beneath the ledge 18 at another point within reach of the cashier but concealed from view by the casual observer. The other terminal 55 of the manual switch is connected by means of the wire 56 to the alarm bell 57, and the circuit is completed from the bell 57 to the battery 50 by means of the wire 58.

Many ways of effecting the alarm circuit will suggest themselves, and one of these which comprises a part of the present invention is shown in Fig. 4 of the drawings. In this embodiment the cash drawer as a whole is designated by the reference numeral 100, and is arranged to slide within the cash register or other container denoted by the numeral 101. The currency guard 125 operates to actuate the automatic switch 129, which is connected by means of the wire 152 with the manual switch 154. From the other terminal

5 of the automatic switch 129, a conductor 151 leads to a point 160 on the side rail 120 which runs upon the rollers 119 carried by the metallic frame of the cash register 101. The conductor 151' secured to the cash register frame as at 161 leads to the battery 159 which is connected by means of the wire 158 to the alarm bell 157.

The means for providing electrical connections from the manual switch 154 to the bell 157 comprises a conductor 155 which passes through an insulated opening 162 in the rear wall of the cash register 101 and the resilient angular conductor 155' which is arranged to be extensible to accommodate the sliding movements of the drawer 100 within the cash register 101 as will be clearly understood from inspection of Fig. 4. Alternatively, the conductor 155' may comprise rigid sections hinged at the joints and operating on the principle of a lazy-tong.

It will be apparent from the present specification that an unauthorized person removing currency from one of the compartments B will cause the guard frame 25 to lift and the finger 40 will close the automatic switch 29, which will remain closed until reset by means of the lever 45. This actuation, assuming that the manual switch 54 is closed, will cause the alarm bell 57 to ring and signal the tampering with the cash drawer. The alarm bell 57 is preferably disposed at a point remote from the cash register, and under these circumstances the burglar will not know that he has sounded the alarm, and may be more readily apprehended.

During business hours or any other periods in which the alarm is not needed, the manual switch 54 may be moved to "off" position.

In Figure 5 of the drawings there is shown a cash drawer 200 having side walls 211 and a rear wall 213. An alarm switch 229 of the type described in the earlier embodiments is provided in the rear wall 213. A manual switch 254 is also installed and the alarm bell is indicated at 257 and a source of current at 250.

An angle iron 220 upon one or both sides of the drawer rides upon the supporting rollers 219, and the current is conducted from the contacts within the drawer through the rail 220, the roller 219 and the frame of the register as in the case of the embodiment shown in Figure 4. Connections are made in the other direction from the switching arrangements within the drawer with a metal bracket 255 which supports a roller 256 which rides upon a rail or metal strip 256' carried by the register frame but insulated therefrom. A conductor 255' completes the circuit from the rail 256' to the battery 250.

It is understood that various changes and modifications may be made in the embodiment of the invention illustrated and described herein without departing from the scope of the invention as defined by the following claims.

Having thus described the invention, what is claimed as new and desired to be secured by Letters Patent is:

1. A protective system for cash drawers, tills, or the like, which comprises, in combination, a guard member carried by the till and adapted to bear against one or more items of currency or the like contained in said till, an electric circuit including a source of current, an electrically actuated signal, and a normally open switch, and connections between said guard and said switch whereby the latter is closed whenever the guard is moved appreciably upon removal of an item of currency.

2. A protective system for cash drawers, tills, or the like, which comprises, in combination, a pivoted guard member carried by the till and adapted to bear down upon one or more items of currency or the like contained in said till, an electric circuit including in series a source of current, an electrically actuated signal, and a normally open switch, and mechanical connections between said guard and said switch whereby the latter is closed whenever the guard is raised appreciably about its pivot upon removal of an item of currency.

3. A protective system for cash drawers, tills, or the like, which comprises, in combination, a guard frame pivoted adjacent its rear end to said till and bearing at its forward end upon currency in a compartment of the till, an electric circuit including in series a source of current, an electrically actuated signal, and a switch device carried by the till adjacent the rear wall of said compartment, and an actuating projection on said guard frame adapted to close said switch device upon pivotal movement of said guard frame as upon removal of said currency.

4. A protective system for cash drawers, tills, or the like, which comprises, in combination, a guard frame pivoted adjacent its rear end to said till and bearing at its forward end upon currency in a compartment of the till, an electric circuit including in series a source of current, an electrically actuated signal, and a switch device carried by the till adjacent the rear wall of said compartment, an actuating projection on said guard frame adapted to close said switch device upon pivotal movement of said guard frame as upon removal of said currency and an overhanging ledge at the rearward portion of said compartment concealing said switch and actuator.

5. A protective system for cash drawers, tills, or the like, which comprises, in combination, a guard frame pivoted adjacent its rear end to said till and bearing at its forward end upon currency in a compartment of the till, an electric circuit including in series a source of current, an electrically actuated signal, and a switch device carried by the till adjacent the rear wall of said compartment, an actuating projection on said guard frame adapted to close said switch device upon pivotal movement of said guard frame as upon removal of said currency, and a concealed manually-actuated alarm-disabling switch in said circuit.

6. A protective system for cash drawers, tills, or the like, which comprises, in combination, a guard frame pivoted adjacent its rear end to said till and bearing at its forward end upon currency in a compartment of the till, an electric circuit including in series a source of current, an electrically actuated signal, and a switch device carried by the rear wall of said compartment and comprising a substantially stationary contact element, a reciprocating contact element, and releasable resilient detent means for retaining the latter in any position to which it may be moved, an actuating projection on said guard frame adapted to move said reciprocating element of said switch device upon pivotal movement of said guard frame as upon removal of said currency, and manually actuated resetting means for moving the reciprocating switch contact element to open position after a closing actuation.

7. A protective system for cash drawers, tills, or the like, which comprises, in combination, a guard frame pivoted adjacent its rear end to said till and bearing at its forward end upon currency

in a compartment of the till, an electric circuit including in series a source of current, an electrically actuated signal, and a switch device carried by the rear wall of said compartment and comprising a substantially stationary contact element, a reciprocating contact element, and releasable resilient detent means for retaining the latter in any position to which it may be moved, an actuating projection on said guard frame adapted to close said switch device upon pivotal movement of said guard frame as upon removal of said currency, and manually actuated means for resetting the movable switch control element to open position after a closing actuation, and means concealing said switch and restoring means from casual inspection.

8. A protective system for cash drawers, tills, or the like, which comprises, in combination, a guard frame pivoted adjacent its rear end to said till and bearing at its forward end upon currency in a compartment of the till, an electric circuit including in series a source of current, an electrically actuated signal, and a switch device carried by the rear wall of said compartment and comprising a pair of resilient blade contact elements disposed side by side with a gap therebetween, a plunger mounted for reciprocation in the space between said elements, a bridging conductor element carried by said plunger and adapted when said plunger is pressed to bear resiliently against said blade contacts and complete the circuit between them thus closing the switch, detent means for resiliently retaining the plunger in switch opening and closing positions, an actuating projection on said guard frame adapted to move said plunger to close said switch device upon pivotal movement of said guard frame as upon removal of said currency, and manually actuated resetting means for moving the plunger to switch opening position after a closing actuation.

9. A burglar alarm for cash registers, in combination, a metal register frame, a cash drawer slideable into and out of said frame, said drawer being made of a non-conducting material, a metal rail secured to at least one side of said drawer and metal supporting rollers rotatably carried by said frame and adapted to support and guide said rail, an electric circuit including a source of current, an electrically actuated alarm signal, a switch carried by said drawer and adapted to be closed by disturbance thereof due to unauthorized handling of the contents of the cash drawer, the alarm signal being disposed at a point outside of the register, the current being completed between said switch and said alarm signal and source of current in one direction by a conductor electrically secured to one of said rails, the said rail, the frame of the register, and a conductor electrically secured to said frame, and in the other direction through an extensible conductor leading from said drawer rearwardly thereof through an insulated opening in the rear wall of said register, said last named conductor adapted to extend and retract upon outward and inward movement of said drawer respectively.

10. A burglar alarm for cash registers, in combination, a metal register frame, a cash drawer slideable into and out of said frame, said drawer being made of a non-conducting material, a metal rail secured to at least one side of said drawer and metal supporting rollers rotatably carried by said frame and adapted to support and guide said rail, a metal supporting rail on said register frame beneath said drawer and insulated from said frame, a metal roller on said drawer adapted

to run on said last named rail, an electric circuit including a source of current, an electrically actuated alarm signal, a switch carried by said drawer and adapted to be closed by disturbance thereof due to unauthorized handling of the contents of the cash drawer, the alarm signal being disposed at a point outside of the register, the current being completed between said switch and said alarm signal and source of current in one direction by a conductor electrically secured to one of said rails, the said rail, the frame of the register, and a conductor electrically secured to said frame, and in the other direction through a conductor leading to said drawer supported roller, and said register supported rail. 15
